(57)

CLAIM

The ornamental design for a football jersey dress as shown and described.

DESCRIPTION

FIG. 1 is a front perspective view showing the design;

FIG. 2 is a front view thereof;

FIG. 3 is a back view hereof;

FIG. 4 is a first side view thereof;

FIG. 5 is a second side view thereof;

FIG. 6 is a top view thereof; and,

FIG. 7 is a bottom view thereof.

The broken lines showing portions of the football jersey dress form no part of the claimed design.
